RAIN PROTECTIVE GARMENT

Benjamin A. Levitt, Newark, N. J., assignor to
A. L. Siegel Co. Inc., New York, N. Y., a cor-
poration of New York

Application September 5, 1945, Serial No. 614,491

4 Claims. (Cl. 2—84)

1

This invention relates to a rain protective garment.

Rain protective garments, especially intended for ladies' use, have been made in a variety of structures and designs out of sheet or film plastics of a transparent and lightweight nature, such that the garment may be folded up into a small package capable of being contained in a lady's handbag, and capable of being readily unfolded for emergency use in inclement weather.

The prime object of my present invention centers about the provision of a rain protective garment of this nature which is exceedingly simple in construction, which may be made by such simple manufacturing and assembling operations as to produce a garment at a very low cost and saleable at a correspondingly low figure, and which, designed to carry out all of the functions and advantages incident to and expected of its construction, is capable also of being produced in an attractive design.

To the accomplishment of this object and such other objects as may hereinafter appear, my invention relates to the rain protective garment sought to be defined in the appended claims and described in the following specification taken together with the accompanying drawing in which:

Fig. 1 is a perspective view of the rain protective garment of my present invention, showing the shape and form it assumes during use on the wearer;

Fig. 2 is a view of two sheet patterns used in making up the garment;

Fig. 3 is a fragmentary view shown on an enlarged scale and taken in cross-section in the plane of the line 3—3 of Fig. 1;

Fig. 4 is a similar view taken in cross-section in the plane of the line 4—4 of Fig. 1; and

Fig. 5 is a similar view taken in cross-section in the plane of the line 5—5 of Fig. 1.

Referring now more in detail to the drawing and having reference first to Figs. 1 and 2 thereof, the rain protective garment of the present invention comprises a body generally designated as B made from two similarly dimensioned sheet patterns p and p', the blanks of which are shown in Fig. 2 of the drawing. The body B defines in the garment assembly a head section generally designated as H and a cape section generally designated as C, the region between these sections forming or defining the neck N of the garment. It is a characteristic feature of the present invention that the garment body B is made from the two similarly dimensioned sheet patterns p and p', superimposed one on the other, attached to each

2

other by suitable binding, then finished off by an added edge binding, and then provided with a simple neckband and arm loops to produce the finished structure depicted in Fig. 1 of the drawing, which finished structure may be laid out in the flat and folded into a small package for handbag storage use.

The material used for the sheet patterns p and p', is a waterproof transparent lightweight plastic film or similar substance such, for example, as the rubber hydrochloride plastic film product known as "Pliofilm." Any similar sheeted or film material of a waterproof or lightweight nature may be employed. The "Pliofilm" type of plastic film is particularly advantageous because in addition to having the desired lightweight, transparent and waterproofing properties is quite durable and strong.

The sheet patterns p and p', similarly dimensioned as stated, and one being a negative of the other (one a right hand pattern and the other a left hand pattern), may be contoured as shown in Fig. 2 of the drawing, and when so contoured are provided with the corresponding bottom edges b and b', the corresponding front edges f and f', and the corresponding rear edges r and r', the front and rear edges converging and merging at the tops t and t', of the patterns.

The two patterns p and p', are then assembled to produce the finished garment shown in Fig. 1 by the following simple manufacturing steps:

(1) The two sheet patterns are united together along their rear edges r and r', by a binding strip 10, which may be made of a textile fabric material and which is channeled as depicted in Fig. 5, the binding strip being stitched to the rear edges r and r', of the two patterned sheets by a line of stitching 12 reaching from the bottom 14 of the garment cape section to the top 16 of the garment hood section. This single binding strip unites together the two patterned sheets p and p';

(2) The front edges f and f', of the patterns have an elastic binding 18 stitched thereto at the hood section H of the garment by means of an uninterrupted line of stitching 20, the binding and stitching circlingly extending about the hood section H and terminating at their lower ends at the garment neck N. The elastic binding 18 (see also Fig. 4) may be a textile fabric binding containing rubber or may be any other type of elastic binding which when stitched to the front edges of the hood portion effects a gathering of these front edges such as to produce a cupped and form-fitting hood for the head of

the user, as is illustrated in Fig. 1 of the drawing;

(3) The body of the garment is then finished off by attaching to the remaining front edges *f* and *f'*, and to the bottom edges *b* and *b'*, of the patterned sheets a binding strip 22, which is made of a material similar to the binding 10 strip (see also Fig. 3), and which binding strip is preferably stitched uninterruptedly by means of a line of stitching 24 along the front and rear edges 10 *f*, *b*, *b'* and *f'*. The binding strip 22 terminates at its two ends at the neck *N* of the garment. Preferably at these terminating ends the binding strip ends are doubled over and stitched to produce loop elements 26 and 28; and

(4) The final finishing touches are made by attaching a tie string 30 at the garment neck to produce a neckband and by forming the arm inserting loops 32, 32 at the front edges of the cape section of the garment. This is accomplished merely by encircling the neck *N* with a tape or tie string 30, preferably stitching the same to the rear binding strip 10 as at 34 and drawing or threading the ends of the tie string through the loops 26 and 28, the tie string then forming a draw string for the neck of the garment at the neck of the user. The arm inserting loops 32, 32 are produced merely by attaching two pieces of tape at their opposite ends to appropriate parts of the binding tape 22 at the front edges of the cape section *C* of the garment.

The rain protective garment of my present invention, the manner of manufacturing the same, and the advantages, both manufacturing and utilitarian, will in the main be fully apparent from the above-detailed description thereof. Being made from two similarly dimensioned sheet patterns, one superimposed on the other, the garment may be readily laid out in the flat notwithstanding the gathering edges at the hood section and may be quickly and readily folded and refolded from this flat condition into small confines to produce a correspondingly small as well as neat package for handbag or other storage use. When unfolded and set up for rain protective use, an attractive and fully functionable hood and cape garment is obtained. The hood, by dint of the construction described, closely fits the head and face of the user, may be neatly caused to encircle the neck and be tucked under the chin of the user by means of the draw string 30, and may be held to the body of the user by the user inserting her arms through the loops formed by the tape pieces 32, 32. The garment is made by the exceedingly simple manufacturing operations above sequentially described. A garment is obtained which has a binding ornament along all of its open edges, the ornamental binding being balanced by the binding which secures together the two patterned sheets out of which the garment is made.

It will be apparent that changes may be made in the described construction without departing from the spirit of the invention defined in the following claims.

I claim:

1. A rain protective garment comprising a body made of waterproof sheet material, said body

5 consisting of two similarly dimensioned sheet patterns, one superimposed on the other, defining in the garment assembly a hood section and a cape section, the region between the hood section and the cape section defining the neck of the garment, each sheet pattern having a bottom edge, a rear edge and a front edge, the rear and front edges converging and merging at the top, the two sheet patterns being united together along their rear edges by a binding stitched thereto, the front edges at the hood section of the garment having an elastic binding stitched thereto and thereby producing a cupped and head fitting hood, the front edges together with the bottom edges at the cape section having a binding stitched therewith, and a tie string attached to the neck of the garment forming a neckband.

2. A rain protective garment comprising a body made of waterproof sheet material, said body consisting of two similarly dimensioned sheet patterns, one superimposed on the other, defining in the garment assembly a hood section and a cape section, the region between the hood section and the cape section defining the neck of the garment, each sheet pattern having a bottom edge, a rear edge and a front edge, the rear and front edges converging and merging at the top, the two sheet patterns being united together along their rear edges by a binding stitched thereto, the front edges at the hood section of the garment having stitched thereto an uninterrupted elastic binding terminating at the garment neck and thereby producing a cupped and head fitting hood, the front edges together with the bottom edges at the cape section having an uninterrupted binding stitched therewith, and a tie string attached to the neck of the garment forming a neckband.

3. The rain protective garment of claim 2 in which the last mentioned binding terminates in loops at the garment neck, and the tie string stitched to the rear binding is drawn through said loops.

4. A rain protective garment comprising a body made of waterproof sheet material, said body consisting of two similarly dimensioned sheet patterns, one superimposed on the other, defining in the garment assembly a hood section and a cape section, the region between the hood section and the cape section defining the neck of the garment, each sheet pattern having a bottom edge, a rear edge and a front edge, the rear and front edges converging and merging at the top, the two sheet patterns being united together along their rear edges by a binding stitched thereto, the front edges at the hood section of the garment having stitched thereto an elastic binding terminating at the garment neck and thereby producing a cupped and head fitting hood, the front edges together with the bottom edges at the cape section having a binding stitched therewith, and terminating at the garment neck in loops, a tie string attached at the neck of the garment to the rear binding and drawn through said loops, and pieces attached to the front bindings at the cape section defining arm receiving loops.

BENJAMIN A. LEVITT.
